PADDLE BALL GAME APPARATUS

Filed Jan. 2, 1925

FIG. 7.

FIG. 3.

FIG. 2.

INVENTOR

Andrew L. Thompson
BY
John W. Maupin.

ATTORNEY

UNITED STATES PATENT OFFICE.

ANDREW L. THOMPSON, OF SEATTLE, WASHINGTON.

PADDLE-BALL-GAME APPARATUS.

Application filed January 2, 1925. Serial No. 49.

My invention relates to paddle ball game apparatus and the objects of the invention are to provide a simple and inexpensive game of skill simulating the well known game of base ball. The game may be played by any number of persons, young or old, either in or out of doors, and is intended to afford pleasure and amusement as well as to provide bodily movement and beneficial exercise for the players.

With the above and other objects in view which will appear as the description proceeds, the invention consists of the novel arrangement, combination and adaptation of parts herinafter described and claimed. These objects are accomplished by devices illustrated in the accompanying drawings; wherein:—

Figure 1 is a view in perspective of the apparatus embodying the features of the invention;

Fig. 2 is a plan view showing the same idea as adapted to a different system of scoring; and

Fig. 3 is a view in central longitudinal vertical section showing the ball in one of the pockets.

Referring to the drawings throughout which like reference numerals designate like parts, the numeral 5 indicates a paddle or base member that is provided with a handle member 6. For the purpose of combining strength, durability and lightness, said paddle is preferably made of three-ply veneered wood.

The paddle member 5 is provided with a plurality of shallow saucer like pockets so positioned as to represent a base ball "diamond" on a miniature scale. The pocket adjacent the handle, as designated by the numeral 7, is the "home plate", and in counter clockwise direction the numeral 8 indicates "first base", the numeral 9 "second base", and the numeral 10 "third base".

For the purpose of adding interest and zest to the game I have provided a plurality of standing pins or pegs 11 that are driven or screwed into the base member 5 between the "bases" and slightly outside the direct path or line between same. One of said pins is placed between first and second base

and between second and third base respectively while two are positioned between third base and home plate for reasons presently set forth.

55

The game is played with a ball member 12 preferably made of rubber or other resilient material. The player holds the paddle by the handle in one hand and bounces the ball with the other hand on a table, floor or sidewalk. When the ball rebounds it is caught on the paddle and by slight manipulation is caused to settle in the pocket 7 or "home plate".

60

In order to move the ball out of the "home" pocket the paddle is gently tilted and then by slightly jiggling same the ball is caused to move into the "first base" pocket 8 which counts a score of five points. By the same means the ball is caused to move 70 successively to "second base", "third base", and finally to "home plate", scoring ten, fifteen, and twenty-five points in all.

65

It will be understood that the ball must be brought to a standstill in each pocket, 75 and that same must pass on the outside of each of the pins 11. This necessitates the ball passing closer to the edge of the paddle member particularly between "third base" and "home plate" where two pins are stationed and thus makes the game more difficult to play successfully.

70

If the ball falls off the paddle, or if the player touches the ball, or causes the ball to enter any pocket out of regular consecutive 85 order he is "out" and the paddle passes to the next player. The first person, or side provided partners are playing, who scores one hundred points will win the game.

80

In Fig. 2 of the drawings the characters 90 designated by the numeral 13 represent playing card denominations, and it will be apparent that the game may be readily adapted to such card games as "bridge whist" or the like by simply using scores and 95 points adaptable thereto.

90

While I have described the invention with some particularity it will be understood that I intend no limitations except in so far as are imposed by the appended claim, and 100 that such changes may be resorted to as are within its scope and spirit.

Having thus described my invention what I claim and desire to secure by Letters Patent of the United States is:—

A paddle ball game apparatus comprising a paddle member having a handle, said member having saucer like pockets arranged to simulate a base ball diamond, a plurality of pins disposed between said pockets out-

side the lines between same in consecutive order, and a resilient ball member substantially as and for the purpose set forth. ¹⁰

In witness whereof, I hereunto subscribe my name this 18th day of December A. D. 1924.

ANDREW L. THOMPSON.
